UNITED STATES PATENT OFFICE.

ALEXANDER A. MALYSKO, OF CHICAGO, ILLINOIS.

DESK-CALENDAR STAND.

1,250,479.

Specification of Letters Patent.

Patented Dec. 18, 1917.

Application filed July 3, 1917. Serial No. 178,470.

To all whom it may concern:

Be it known that I, ALEXANDER A. MALYSKO, a citizen of the United States, residing at Chicago, in the county of Cook and State 5 of Illinois, have invented new and useful Improvements in Desk-Calendar Stands, of which the following is a specification.

This invention relates to stands for desk 10 calendars composed of a pad of calendar leaves which are successively turned over to expose the succeeding leaves. The pad is supported on arched rods so that the leaves may be turned by transferring the same from one side of the arch to the other. The 15 invention has for its object to provide a novel and improved means for attaching the arched rods to a base whereby they are rendered readily removable from the base for the assembly and removal of the calendar 20 leaves.

The object stated is attained by means of a combination and arrangement of parts to be hereinafter described and claimed, and in order that the same may be better understood, reference is had to the accompanying 25 drawing forming a part of this specification.

In the drawing,

Figure 1 is a perspective view of the device; 30 Fig. 2 is a bottom plan view showing the means for securing the arched filing rods, and

Fig. 3 is a cross-section on the line 3—3 of Fig. 2.

Referring specifically to the drawing, 5 denotes a suitable base having a slanting top on which the calendar leaves 6 are supported. From the top of the base rise two arched filing rods 7 on which the leaves are 10 strung, they being provided with perforations adjacent to one edge through which the rods pass. The pad of cards is strung on one leg of the rod, and as each day passes the card bearing the date thereof is 15 slid over the arch to the other leg, face downward, leaving the face of the next card exposed. This is a well-known type of desk calendar, and a further description thereof is not deemed necessary.

In the under side or bottom of the base 5 is a circular recess 8 having a diameter cor-

responding to the distance between the two arched rods 7. One leg of each arch is embedded in the base as shown at 9, and the other leg of each arch extends through a hole 10 in the base leading from the top thereof to the recess 8. The last mentioned legs of the arch extend into the recess 8 a short distance, but of the protruding portion only one half is exposed, the other half being embedded in the stock of the base, the hole 10 being continued in the side wall of the recess and terminating short of the bottom of the base to form a shoulder against which the end of the leg seats, and whereby the leg is prevented from being pushed downward too far. A portion of one of the legs of each arched rod is thus exposed in the recess 8, and in said exposed portion is a keeper notch 11 for a latch bar 12 mounted in the recess to swing about a central pivot screw 13. The length of the latch bar is such that when it is swung to extend between the two protruding leg ends, it seats in the notches 11 and thus prevents the arched rods from being pulled upward out of the base 5. When it becomes necessary to remove the leaves 6, the latch bar 12 is swung clear of the notches 11, whereupon the arched rods are released for removal from the base 5. The latch bar has a finger piece 14 to facilitate its operation, and it is housed in the recess 8, leaving the under side of the base 5 smooth and entirely free from obstructions.

I claim:

A calendar stand, comprising a base having a bottom recess and openings extending from the top to said recess, and continued through a portion of the side wall of the recess, the lower ends of the openings producing shoulders in the side wall of the recesses, arched filing rods rising from the base and having one of their legs passing through the openings, and abutting against the aforesaid shoulders, the ends of said legs being exposed in the recess and having side notches, and a latch bar pivoted in the recess and engageable with the notches to lock the legs against withdrawal.
